UNITED STATES PATENT OFFICE.

WILLIAM F. DRAPER, OF HOPEDALE, MASSACHUSETTS, ASSIGNOR TO GEORGE DRAPER & SONS, OF SAME PLACE.

SPINDLE-SUPPORT.

SPECIFICATION forming part of Letters Patent No. 484,356, dated October 11, 1892.

Application filed June 6, 1892. Serial No. 435,623. (No model.)

To all whom it may concern:

Be it known that I, WILLIAM F. DRAPER, of Hopedale, county of Worcester, State of Massachusetts, have invented an Improvement in 5 Spindle-Supports, of which the following description, in connection with the accompanying drawings, is a specification, like letters on the drawings representing like parts.

This invention has for its object to improve 10 that class of spindles wherein the tapered lower end of the spindle fits the tapered interior of a bolster-bearing. In this class of spindles provision has been made to allow the fit of the spindle to the bolster-bearing to 15 be changed by raising or lowering the tapered bolster with relation to a fixed step. Heretofore the step has been screwed into the bolster; but to make the adjustment the spindle has had to be removed and tools applied to 20 the bolster, requiring considerable time. To simplify this operation, I have prolonged the shank of the step, which is screwed into the bolster, down below the shank of the bolster-case, and have attached to said step a nut, 25 which is screwed onto the bolster-case shank, so that by rotating said nut the step may be screwed into the lower end of the bolster, and as the latter cannot rotate with the step it is compelled to change its position with relation 30 to it.

Figure 1, in partial vertical section and elevation, represents a structure embodying my invention; and Fig. 2, a section on the line *x*.

35 A is a spindle having a tapering lower end or pintle and provided with a sleeve-whirl A².

B is a supporting-case having an oil-reservoir B' and a threaded shank B², on which is a nut B³, by which to clamp the supporting-case to the usual rail C. The supporting-case contains a loose bolster D, represented as surrounded by a yielding packing D', the said bolster being restrained by the pin or projection D², entering a groove therein, from 40 rotation with the spindle. The bolster is provided at its lower end with screw-threads to receive a threaded step *a*, connected to or forming part of the step-shank *a'*, extended below the lower end of the bolster-case and having 45

50 suitably attached to it a step-nut *a'*, which engages screw-threads of the bolster-case, a check-nut *b* confining the step-nut in adjusted

position. When the bolster becomes worn at its interior by the friction thereon of the spindle, it is necessary, in order to preserve the 55 proper fit between the spindle and bolster, to change the relative positions of the bolster and spindle longitudinally, and to enable the whirl to preserve its usual or established position I have made provision for lifting 60 the bolster to compensate for such wear, and this I effect in this present invention very easily and quickly by engaging the step-nut *a'* and turning it in the direction to screw the step into the bolster-tube, and as the bolster-tube cannot rotate it must necessarily be 65 moved vertically.

Having described my invention, what I claim, and desire to secure by Letters Patent, is—

70 1. A spindle-support consisting of a supporting-case and a bolster mounted therein and restrained as against rotation with the spindle and threaded at its lower end, combined with a threaded step, a step-shank extended 75 below the lower end of the supporting-case and having a step-nut attached thereto and adapted to engage screw-threads below the rail, to operate substantially as described.

2. A spindle-support consisting of a supporting-case and a bolster mounted therein having a taper-bearing and being capable of vertical adjustment with relation to a step-piece, and means to adjust said bolster while the spindle is running, substantially as de- 80 scribed.

85 3. A spindle-support consisting of a supporting-case and a bolster mounted therein and restrained as against rotation with the spindle and threaded at its lower end, combined 90 with a threaded step, a step-shank extended below the lower end of the supporting-case and having a step-nut attached thereto and adapted to engage screw-threads below the rail, and a check-nut to hold said step in 95 position, substantially as described.

In testimony whereof I have signed my name to this specification in the presence of two subscribing witnesses.

WILLIAM F. DRAPER.
